UNITED STATES PATENT OFFICE.

PETER KRUSE, OF BROOKLYN, NEW YORK, ASSIGNOR TO E. W. BLISS COMPANY, OF BROOKLYN, NEW YORK, A CORPORATION OF WEST VIRGINIA.

SHEET-METAL-WORKING MACHINE.

1,242,206.

Specification of Letters Patent.

Patented Oct. 9, 1917.

Application filed October 8, 1915. Serial No. 54,757.

To all whom it may concern:

Be it known that I, PETER KRUSE, a citizen of the United States of America, residing in the borough of Brooklyn, county of 5 Kings, city and State of New York, have invented certain new and useful Improvements in Sheet-Metal-Working Machines, of which the following is a specification.

This invention relates to sheet metal 10 working machines, and aims to provide certain improvements therein.

Improved means for positioning and feeding sheets of metal from one position to another through the machine, are provided by 15 the present invention.

Other features of improvement will be hereinafter referred to.

An embodiment of the invention is shown in the accompanying drawings.

20 The invention has been shown as incorporated in a machine for making can bodies. The invention may, however, be otherwise embodied and otherwise applied.

In said drawings,—

25 Figure 1 is a top plan view of so much of a body making machine as is necessary to illustrate the invention;

Fig. 2 is a side elevation of the construction shown in Fig. 1, with parts in section;

30 Figs. 3 and 4 are respectively a vertical sectional view, and a top plan view, illustrating in detail one embodiment of the improved feeding means;

Figs. 5 and 6 are like views of another 35 embodiment of the improved feeding means;

Fig. 7 shows an end elevation of the machine.

In said drawings, the letter A designates a suitable table or bench forming the frame 40 of the machine, the general construction of the machine being similar to that described in my U. S. Patent No. 1,081,050, dated December 9, 1913.

B, B are a plurality of feed bars working 45 in suitable guide-ways in the top face of the table A, preferably attached to a slide block or piece C, and adapted to be reciprocated by a suitable means, as for instance, a train of links and levers b¹, b², b³ connected

50 to a crank pin b⁴ upon a disk b⁵ mounted upon a main drive-shaft D. The feed bars B, B are provided with a plurality of feed fingers, certain or all of which, as for instance the fingers E, may be formed so as

55 to act to confine, in one direction or in the

other, perpendicularly of the sheet, or in both directions, the edges or margins of the sheets of material X with which they are brought into contact. These feed fingers E may grip the edges of the sheets, as in my 60 aforesaid Patent No. 1,081,050, but preferably do not grip the edges of the sheet, but simply confine the upper or lower, or the upper and lower edge or marginal portions, the feed fingers E being formed with a slot 65 or recess e for the purpose. However, one or other of the parts e⁰ of the fingers E on either side of the recess e may be omitted, where it is desired or necessary to confine the edge portions of the sheets in but one 70 perpendicular direction. Other feed fingers E¹ may be provided, if desired, as for instance, where the sheets of metal are to be fed to an idle position.

The arms E are pivoted upon the feed 75 bars B, as at e¹, and are adapted to be depressed against the pressure of a spring e² as they move rearwardly, being so depressed by the sheets of metal with which they come in contact in moving rearwardly. A stop 80 e³ limits the extent of the projection of the feed finger E above the upper face of the feed bars.

F¹, F², and F³ designate a plurality of mechanisms by which the sheets of metal are 85 worked upon. In the construction illustrated, the mechanism F¹ is a notching mechanism for forming notches in the sides of the sheets of metal, the mechanism F² is a flanging mechanism by which flanges or 90 hooks are formed on the notched sides of the sheets, and F³ is a body forming mechanism comprising a horn G around which the sheets are bent and the ends interlocked and joined in well-known manner. The function 95 of the feed mechanism is to feed the sheets of metal to an exact position with relation to these several mechanisms F¹, F² and F³, it being essential to the formation of a can that the sheets be operated upon at precise 100 points by the several mechanisms, and that the ends of the sheets and the notches therein shall properly match when wrapped around the horn and the ends joined.

Sheets of metal are fed to the machine in 105 any suitable manner (by hand if desired), and are carried forward by the feed fingers upon successive reciprocation of the feed bars B, B. An automatic feed I is shown, the construction of which is fully described 110

in Patent No. 1,081,050 aforesaid. As the feed bars B, B move forward, the sheets of metal X are carried forward by the feed fingers beyond stops H¹, H² and H³ mounted upon a fixed part of the machine. The sheets of metal are preferably moved slightly beyond the stops, and, during the rearward movement of the feed fingers are moved rearwardly against the stops H¹, H² or H³ by suitable means, as by the means P, illustrated in detail in Figs. 3 and 4, or the means Q, illustrated in detail in Figs. 5 and 6.

As shown in detail in Figs. 3 and 4, the means P may comprise a bar or blade p having a cam face p¹ thereon. The bar p is adapted to reciprocate vertically, and to this end it may conveniently be mounted upon a reciprocating part of the notching mechanism F¹, as illustrated at p². The means P act to push the sheet rearwardly against the stops H¹. Ordinary feed fingers E¹ are shown as being employed in conjunction with the means P, though the feed fingers with a recess or notch therein may be employed.

As shown in detail in Figs. 5 and 6, the means Q may comprise a spring-pressed rod q. The rod may be mounted in an adjustable sleeve q¹, by which the position of the end of the rod with relation to the adjacent edge of the sheet may be adjusted. The end of the rod may also be threaded and provided with a nut q² by means of which the tension of the spring q³ may be adjusted. The means Q may be mounted in suitable brackets q⁴ attached to the frame of the machine.

The feed fingers E on their forward movement preferably act to feed the sheets beyond the stops H³ and against the ends of the rods q, the spring q³ being compressed. As the feed fingers E move into engagement with the sheet of metal, the edge portions of the sheets are received in the recesses e of the feed fingers E. The feed fingers and are confined above and below by the feed fingers. As the feed fingers E move rearwardly, the rods q are pressed rearwardly by the springs and move the sheet of metal rearwardly against the stops H³, the sheets being held in the recess e in the fingers E. The sheet is guided in its rearward movement, and prevented from being deflected or bent in such manner as not to be stopped by the stop H³ or to be stopped in the proper position. The feed fingers E with the recesses e therein also in practice act to prevent transverse displacement of the sheet, the width of the recess being such that any transverse pressure on the sheet would cause slight bending or buckling, which would cause the sheet to bind against the walls of the recess.

The construction wherein the sheets of metal are pushed rearwardly against stops, while the edge portions of the sheet during

the rearward movement are embraced, confined or supported by the feed fingers, is of special importance where the ends of the blank are unsupported, as for instance, in the position where the sheets are acted upon by the horn.

The horn G is preferably adapted to be raised and lowered in conjunction with the feeding of the sheets, as described in the patent hereinbefore referred to, the horn being mounted upon a slide g which is raised by another slide f, the slide f being actuated by a lever f² connected to a rod f³, the rod being connected to a crank lever f⁴ actuated by a cam f⁵ on the shaft D. The slide g is pressed down by a spring g¹ carried in a part g² attached to a fixed part of the machine. The raising of the horn G allows the feeding and positioning movements of the sheets X to take place without interference by the horn. When the sheets are fed beneath the horn, an abutment g³ is preferably provided, which acts as a support when the sheets are being fed beneath the horn, and also acts as an abutment against which the sheets may be clamped by the horn.

Strips b' are preferably provided, which are adapted to bear upon the upper sides of the sheets X with slight friction, the friction, however, not being sufficient to prevent the feeding or positioning movements of the sheets.

The operation of the device is as follows:—The sheets of metal are engaged by the feed fingers E or E¹, the adjacent marginal portions of the sheets fitting within the recesses e of the feed fingers E. The sheets are carried forward beyond, and preferably slightly beyond, the stops H¹, H² or H³. The sheets are then acted upon by the means P or Q, and pushed rearwardly against the stops. The means Q act to push the sheet rearwardly while the edge or marginal portions are still in the recesses e in the feed fingers E, the edges of the sheet being thereby prevented from being deflected up or down while moving against the stops. The horn G is preferably raised while the sheets are being fed and positioned under the same. When in position with reference to the mechanisms F¹, F² and F³, the sheets are suitably acted upon by said mechanisms.

The inventive ideas are capable of receiving other embodiments than those specifically illustrated and described.

The embodiment shown in Figs. 3 and 4 is set forth and claimed in a divisional application Serial No. 89,047, filed April 5, 1916.

What is claimed is:—

1. In sheet metal working machines, the combination of a relatively narrow support, a reciprocatory feed means adapted to feed a sheet of metal over said support with its edges projecting into space on each side of

- said support, said reciprocatory feed means comprising feed fingers having means thereon for supporting the projecting portions of said sheet when fed over said narrow support to prevent sag, stops for preventing back movement of said sheet, and means independent of said feed fingers for setting said sheet back against said back stop.
2. In sheet metal working machines, the combination of a relatively narrow support, a reciprocatory feed means adapted to feed a sheet of metal over said support with its edges projecting into space on each side of said support, said reciprocatory feed means comprising feed fingers having means thereon for supporting the projecting portions of said sheet when fed over said narrow support to prevent sag, stops for preventing back movement of said sheet, and means independent of said feed fingers for setting said sheet back against said back stop, said back-setting means comprising a spring-pressed rod acting in the line of advance of the sheet.
3. In sheet metal working machines, the combination of a relatively narrow support, a reciprocatory feed means adapted to feed a sheet of metal over said support with its edges projecting into space on each side of said support, said reciprocatory feed means comprising feed fingers having recessed portions for supporting the projecting portions of said sheet when fed over said narrow support to prevent sag, stops for preventing back movement of said sheet, and means independent of said feed fingers for setting said sheet back against said back stop.
4. In sheet metal working machines, the combination of a relatively narrow support, a reciprocatory feed means adapted to feed a sheet of metal over said support with its edges projecting into space on each side of said support, said reciprocatory feed means comprising feed fingers having recessed portions for supporting the projecting portions of said sheet when fed over said narrow support to prevent sag, stops for preventing back movement of said sheet, and means independent of said feed fingers for setting said sheet back against said back stop, said back-setting means comprising a spring-pressed rod acting in the line of advance of the sheet.
- In witness whereof, I have hereunto signed my name in the presence of two subscribing witnesses.

PETER KRUSE.
